United States Patent Office.

CHARLES WILLIAMS, OF JACKSON, MISSISSIPPI.

Letters Patent No. 79,532, dated June 30, 1868.

IMPROVEMENT IN ATTACHING HANDLES TO MOULD-BOARDS OF PLOWS.

The Schedule referred to in these Letters Patent and making part of the same.

TO ALL WHOM IT MAY CONCERN:

Be it known that I, CHARLES WILLIAMS, of the city of Jackson, in the county of Hinds, and in the State of Mississippi, have invented a new and improved Mode of Attaching Handles to Mould-Boards of Plows; and do hereby declare that the following is a full, clear, and exact description thereof, reference being had to the accompanying drawings, making part of this specification, in which—

Figure 1 represents a side view of my invention, and

Figure 2 is an end or rear view, showing the handle attached to the lugs.

I will now proceed to describe its construction and operation.

My improvement consists in the peculiar mode of attaching the handles to the mould-boards of plows, by which means the torsive strain may be avoided.

It is well known to all who are familiar with farming that handles secured in the usual manner are subjected to an intense strain, which soon separates the fibres, thereby rendering the handles useless. In my improvement I cast two iron lugs to the mould-board around wrought-iron rods. On one end of each I cut screws and provide them with nuts. These bolts may have a thread cut on both ends, and the lugs may be cast solid and drilled subsequently, and a screw cut in them to receive the bolt.

In case of accident, whereby one or more of the bolts may be broken, new ones may be supplied at a trifling cost. In the event of either of the handles being broken by accident, any ordinary farm-hand, not a mechanic, can replace the handles in a very short time by the aid of a drawing-knife, saw, auger, and wrench.

Having described the construction and operation of my invention, what I claim, and desire to secure by Letters Patent, is—

The lugs *a a*, bolts *d d*, nuts *c c*, and handle *e*, the whole combined, arranged, and operated substantially in the manner herein shown and described, and for the purpose set forth.

In testimony that I claim the foregoing, I have hereunto set my hand, this 13th day of April, 1868.

C. WILLIAMS.
